UNITED STATES PATENT OFFICE.

HARRY P. EFFERTZ, OF UNION HILL, NEW JERSEY.

BOAT PROPULSION.

Application filed May 14, 1923. Serial No. 638,707.

To all whom it may concern:

Be it known that I, HARRY P. EFFERTZ, a citizen of the United States, residing at Union Hill, in the county of Hudson and State of New Jersey, have invented certain new and useful Improvements in Boat Propulsions, of which the following is a specification.

This invention relates to the propulsion 10 of boats, canoes, or other analogous devices, and has particular reference to means whereby a person may propel a boat by hand operated means applied through simple mechanism including gearing and a rotary propeller as distinguished from the use of oars 15 or paddles, and while the operator is facing toward the bow.

A further object of the invention is to provide novel power transmitting means between the hand operated members and the 20 propeller having facilities for the reversal of the propeller without reversing the direction of movement of the hands.

A still further object of the invention is 25 to provide means acting through the propeller for constituting the same as a brake or speed reducing or direction reversing mechanism, either independently of the hand crank operating means or without reversing the 30 direction of movement of such means.

More specifically, the mechanism includes a peculiarly arranged balance wheel for stabilizing the mechanism and craft operated thereby and also serving to check the speed 35 of the boat by virtue of the power stored therein during the normal forward operation of the mechanism.

With the foregoing and other objects in view the invention consists in the arrangement and combination of parts hereinafter described and claimed, and while the invention is not restricted to the exact details of construction disclosed or suggested herein, still for the purpose of illustrating a practical embodiment thereof reference is had 45 to the accompanying drawings, in which like reference characters designate the same parts in the several views, and in which—

Figure 1 is a diagram illustrating in side 50 elevation the application of my improvement to a canoe.

Fig. 2 is a vertical sectional view through the main parts of the mechanism.

Fig. 3 is a rear elevation, partly in section, 55 of the driving head and parts journaled therein.

Fig. 4 is a plan view of the power transmitting mechanism.

Fig. 5 is a plan view, partly in section, of the 60 sliding clutch mechanism.

Fig. 6 is a horizontal sectional detail on the line 6—6 of Fig. 2.

Referring now more specifically to the drawings I show my improved mechanism as comprising a casing 10 designed to be 65 built or introduced into the bottom of a boat, the casing being preferably of cylindrical form and having a removable cover plate 11 for keeping the parts within the casing suitably lubricated and protected from outside 70 influences or conditions, as well as to protect the operator from contact with the parts within the casing. This casing may be supported and secured in desired position by any suitable means.

Journaled in a step bearing 12 in the center of the bottom of the casing is a substantially vertical shaft 13 having a bearing 14 of any suitable nature in the central hub portion 15 of the cover plate. Fixed in any 80 suitable manner to this shaft 13 within the casing is a fly wheel 16 operating substantially in a horizontal plane and of sufficient mass to serve to balance the mechanism and so stabilize the craft as a result of the rotation thereof in said plane, well down toward the bottom of the boat or the like. Associated with the fly wheel or the shaft 13 is a gear wheel 17, shown as a mitre gear, meshing with a similar gear 18 just back of the 90 shaft.

Extending upward from the cover plate is a hollow pedestal 19 bearing at its upper end a hollow head 20 in the nature of a gear casing. Within the pedestal is arranged an 95 extension 13' of the shaft 13, the two parts being connected at a joint 21 near the cover plate.

Journaled in the side plates of the head 20 in suitable packed bearings 22 is a shaft 23 to the ends of which are fastened hand cranks 24. Fixed to the shaft 23 within the head is a gear 25 meshing with a pinion 26 on the upper end of the shaft extension 13', whereby with the rotation of the cranks in the most convenient forward direction by the person seated just at the rear of the pedestal, the shaft 13 will be rotated at relatively high speed in the direction suggested by the arrows on the several figures. It will be understood that the size and position of the pedestal and driving mechanism will be ar-

ranged most conveniently for the operator. During normal forward driving operation both hands will of course be applied to the cranks but for the control of the craft either hand may be relied upon to maintain the forward movement in connection with the power stored in the fly wheel. Thus it will be understood that the fly wheel will have a constant direction of movement resulting directly from the forward operation of the cranks as just above indicated.

27 indicates a rotary propeller of any suitable design or construction fixed upon a propeller shaft 28 extending rearward through a suitably packed housing or gland 29. 30 indicates an auxilliary propeller shaft journaled within the casing 10 in alignment with the propeller shaft 28, the shafts being held in precise alignment by a suitable means such as an extension 31 of one shaft member journaled within a similarly formed socket 32 in the other shaft member. The gear 18 already described is fixed to the forward end of the shaft 30 and hence such shaft is always positively driven in a predetermined direction when the fly wheel and its shaft are in motion.

As a suitable means to transmit the power from the fly wheel and shaft through the mitre gears aforesaid to the propeller, providing for both the forward and reverse driving effects, I show a double clutch cone 33 splined for sliding but non-rotative connection with the shaft 30. That is to say, the cone 33 is free to slide endwise but is held from rotation independently of the shaft. 34 indicates a clutch head fixed in any suitable manner, as by a set screw 35, to the propeller shaft 28 at or just back of the joint between the two shafts. 36 indicates a hand lever suitably swiveled in the cover plate 11 within easy reach of the operator, typifying one convenient means for manipulating the clutch mechanism. The operation of this lever in a forward direction will effect the movement of the parts in the direction of the arrows *a*, the clutch cone 33 being thereby shifted rearward, causing the gripping members 37 pivoted to the clutch hub 34 to make driving connection between the two shafts 28 and 30. The ends of these fingers may be dropped into a groove 38 making the connection self retaining.

39 indicates another clutch hub journaled normally loosely upon the shaft 30 in front of the cone 33, but having a set of fingers 40 through which this hub 39 may be connected to the shaft 30 when the cone is shifted forward in the direction of the arrow *b*. The clutch fingers 37 will of course then be disconnected rotatably from the cone 33. 41 is a counter shaft journaled at one side of the shaft 30 and having at its forward end a small gear 42 and at its rear end a larger gear 43. The latter gear meshes constantly

with a gear 44 fixed to the clutch hub 34. Fixed to the clutch hub 39 is a gear 45 which drives the gear 42 through an idler pinion 46 journaled on a stub shaft 47. During the normal forward driving action the gears just mentioned may all run idly, being driven from the gear 44. When, however, the clutch cone is shifted forward according to direction *b* and the clutch hub 39 so connected to the driving shaft 30, the power coming from or through the fly wheel will be exerted directly upon the propeller 27 through the gears 45, 46, 42, 43, and 44. From the design of the gears just mentioned it will be noted that the propeller will be driven at a higher rate of speed through this indirect connection than it is operated in the normal forward direction, and furthermore that the direction of movement of the cranks 24 will continue the same as usual. If now the operator has an emergency demand for the reversal of the machine, he has but to shift the lever 36 rearward as above explained, leaving the power stored in the fly wheel free to be exerted for the driving of the propeller in this reverse direction at high speed. If the power thus stored in the fly wheel is insufficient for stopping or reversing the boat, such power may be augmented by the operation of the cranks in the normal direction.

Moreover, for backing the boat or for starting the boat at low speed in the reverse direction the lever 36 will be shifted rearward as just described and power will be applied to the cranks for this purpose. For locking the clutch mechanism in the reverse direction the fingers 40 will co-operate with the cone in a groove 38'.

Taking advantage of the fact that canoes are ordinarily built along standard lines or sizes, I have provided a most convenient means of attaching my improvement to a canoe as indicated at C, this means comprising a section *c* of the canoe hull having associated therewith my improved propelling and reversing mechanism as a unit. This mechanism includes not only the propeller and operating means therefor but also a balanced rudder 48 connected to a rudder shaft 49 extending upward in the usual manner. I provide also a guard 50 extending downward and forward beneath the movable parts of the controlling mechanism and constituting in effect an extension of the keel piece of the boat. The section *c* is designed to be attached by means of watertight means into a space cut directly out of the boat hull at 51, an expedient easily performed by any mechanic or any other person familiar with tools.

The casing 10 and head 20 as well as the pedestal parts between them being all constructed oil tight, it is expedient for a suitable supply of lubricant in the nature

of oil to be maintained in the same for lubricating the several co-operating parts already described. To this end I show associated with the lower end of the shaft 13

5 a slideable piston 52 co-operating with an eccentric pump cylinder 53 constituting an extension of the bearing portion at the bottom of the casing 10. Oil from the cylinder 53 will thus be forced continually through 10 a tube 54 which may lead upward in any suitable direction to a fork 55 whence the oil is delivered to the two bearings 22 at the head and thence it will drain back again past the step bearing 12' adjacent to the 15 pinion 26 and through the pedestal so as to lubricate the gears 17 and 18 as well as the other parts within the casing, and return finally into the cylinder 53 through a port 56. The lubricating system there- 20 fore will be both automatic and dependable, making the mechanism easily operable for a long period of time without attention. In connection with the clutch mechanism for controlling the reversing of the power 25 it is to be noted that the driving connection between the stored power of the fly wheel and the propeller is frictional and not positive, rendering it impossible for any break- 30 age or other disaster to the mechanism to result from a too sudden application of the stored power for reversing or speed check- 35 ing purposes. In other words, in the event of an emergency demanding the reversing or stopping of the machine, the operator will simply throw the lever 36 rearward without being required to give careful at- tention to the speed with which he makes such lever movement, and the stored power

of the fly wheel will operate practically au- 40 tomatically for producing the desired re- sult.

I claim:

1. In propulsion mechanism, the combina- 45 tion with a casing, of a fly wheel mounted horizontally in the casing, a vertical shaft 45 fixed to the fly wheel, a vertical tubular standard on the casing, a vertical drive shaft in the standard coupled to the fly wheel shaft, a pinion fixed to turn with the fly wheel, a propeller shaft projecting 50 into the casing, a pinion meshing with the first mentioned pinion, an auxiliary shaft fixed to the last mentioned pinion and in line with the propeller shaft, and clutch mechanism in the casing connecting the last 55 mentioned shaft with the auxiliary shaft.

2. In propulsion mechanism, the combi- 60 nation with a casing, of a fly wheel mounted horizontally in the casing, a vertical shaft fixed to the fly wheel, a vertical tubu- 60 lar standard on the casing, a vertical drive shaft in the standard coupled to the fly wheel shaft, a pinion fixed to turn with the fly wheel, a propeller shaft projecting 65 into the casing, a pinion meshing with the 65 first mentioned pinion, an auxiliary shaft fixed to the last mentioned pinion and in line with the propeller shaft, clutch mecha- 70 nism in the casing connecting the last men- tioned shaft with the auxiliary shaft, a lever fulcrumed in the top of the casing and controlling the clutch.

In testimony whereof I affix my signature.

HARRY P. EFFERTZ.
